(57) CLAIM

The ornamental design for slide lighter, as shown and described.

DESCRIPTION

FIG. 1 is a front view showing the slide lighter of my new design;

FIG. 2 is a rear view thereof;

FIG. 3 is a top view thereof;

FIG. 4 is a left side view thereof, the right side view being the mirror image thereof; and,

FIG. 5 is a left side view similar to that of FIG. 4, depicting the slide lighter of my new design positioned for operation.
